(57) CLAIM

The ornamental design for a shoe as shown and described.

DESCRIPTION

FIG. 1 is a top front side perspective view of a shoe showing my new design;

FIG. 2 is a left side view of the shoe;

FIG. 3 is a right side view of the shoe;

FIG. 4 is a front view of the shoe;

FIG. 5 is a rear view of the shoe;

FIG. 6 is a top view of the shoe; and,

FIG. 7 is a bottom view of the shoe.

The broken lines in drawings represent portions of the shoe that form no part of the claimed design.

1 Claim, 6 Drawing Sheets
